27 By Otto M. Kirsch, Atty.

UNITED STATES PATENT OFFICE.

CHARLES J. HOHMAN, SR., OF ELMHURST, ILLINOIS.

GUIDE RAIL.

Application filed August 17, 1922. Serial No. 582,349.

To all whom it may concern:

Be it known that I, CHARLES J. HOHMAN, Sr., a citizen of the United States, residing at Elmhurst, in the county of Du Page and State of Illinois, have invented a certain new 5 new and useful Improvement in Guide Rails, of which the following is a full, clear, concise, and exact description, reference being had to the accompanying drawings, forming 10 a part of this specification.

The invention primarily relates to improvements in guard rail structures such as are ordinarily employed to guard and prevent a railroad train or one of the cars 15 forming the train from jumping or leaving the rails as it travels over a railroad crossing, switch or other structure.

The structure particularly relates to the block ordinarily employed to maintain the 20 guard rail in spaced and associated relation to the main rails forming the track, and has among its various objects the provision of a construction which will successfully resist the various strains applied to the guard rail 25 during the period in which it is called upon to perform its function and thereby maintain said guard rail in its proper vertical position and which will eliminate any relative movement of the guard rail and thereby 30 reduce the probability of accidents.

The invention has as a further object the provision of a block which permits the ready association and disassociation of a clamping element and other elements entering into the 35 guard rail structure.

In addition to the above enumerated objects, it is an object to provide the block with a means whereby the block and clamping elements are held in associated or co-operative relation and to construct the 40 clamping element so that it will resist the strains applied to it, the block and guard rail.

The invention will be explained and more 45 readily understood when read in conjunction with the accompanying drawings which illustrate one embodiment of which the invention is susceptible, it being obvious that changes and modifications may be resorted 50 to without departing from the spirit of the appended claims forming a part hereof.

In the drawings Figure 1 is a top plan view of a portion of a rail and guide rail having the invention applied thereto.

55 Figure 2 is an end view of the structure

shown in Figure 1 showing the rails in section.

Figure 3 is a section taken on line 3—3 of Figure 2, a portion of the structure being 60 shown in elevation.

Figure 4 is a bottom plan view of the structure shown in Figures 1, 2 and 3.

Figure 5 is a perspective view of one of the spacer blocks which may be employed.

The structure illustrated in the drawings 65 includes spacer blocks 10, 11 and 12. These spacer blocks substantially conform in construction with each other and are designed to be arranged between the rail and guide rail and are constructed so as to distribute 70 the strains applied to the guide rail so that the latter will at all times be maintained in proper relation with the remainder of the structure.

Each of the spacer blocks 10, 11 and 12 75 includes a body portion which conforms with the contour of the space provided between the rail and guide rail as clearly shown in Figure 2, and in addition is provided with a portion designed to engage the 80 lowermost face of the lower flanges of the rails. The uppermost faces of the spacer blocks are each provided with a grooved or recessed portion 13 which will receive the flange of a wheel.

The design of these blocks provides faces 85 14, 15, 16 and 17 which respectively contact with the under surface of the head and one face of the web of the rail.

The contour of the block also produces the 90 faces 18—18 which engage the upper surfaces of the flanges of said rails. A transversely arranged portion 20 is employed and is connected to the body of the block by means of the neck 19.

The transverse portions 20 are designed 95 to be arranged below the flange of the rails and to engage the lowermost face of said flanges.

The spacer blocks 10 11 and 12 are each 100 provided with a plurality of these transverse extensions 20, which project downwardly a suitable distance so as to permit of their engagement with the ties 21—21 of the road bed.

The arrangement of elements just described cooperates to maintain the various portions entering into the structure in their proper cooperative relation, and produces a 105 rigid structure which will readily withstand 110

the strains applied thereto, and which will materially lessen the attention necessary to keep the structure in operative condition.

The blocks may be held with relation to 5 the rails by means of the nut and bolts 22 which permit the parts to be readily disassembled when this is found necessary or desirable.

The bolt is held against rotation by means 10 of a plate 23 which is provided with a recess 24 into which the head of the bolt is arranged. This plate is of a dimension sufficient to engage the underside of the head of the rail and one of the flanges of the rail 15 and therefore will be held against relative movement with respect to the rail.

If so desired, a clamping structure may be employed to maintain the blocks and said rails in their proper cooperative relation.

20 This clamping structure may include the clamping elements 25 and 26 and the nut and bolt structure 27 which holds the clamping elements in their proper relation with respect to each other and the rails.

25 When the clamping structure above referred to is utilized, a portion of one of these elements will be arranged in the space 28 provided between a pair of the extensions 20 as clearly shown in Figures 3 and 4, 30 which will prevent relative movement of said clamping element, the block and the remainder of the structure.

The clamping elements 25 and 26 are provided with the upwardly extending portions 35 respectively designated 29 and 30 and respectively engage the web of the rails and in addition are respectively provided with the recessed portions 31 and 32 for the purpose of receiving one of the lowermost 40 flanges of each of said rails.

The clamping element 25 is provided with an extension 33 which is designed to be arranged in the space 28 provided between a pair of the elements 20-20. Thus this portion of the clamping element will be held against relative movement with respect to the block, yet will permit it to be removed from the structure when this is found necessary or desirable.

45 From the foregoing description it is manifest that a simple arrangement is provided for securely holding a spacer block with relation to a rail and a guide rail.

It is further evident that any strains applied to the guide rail will be successfully re-

sisted and that said rail will be maintained in its proper vertical position and that the structure provides the necessary rigidity to prevent the occurrence of accidents which are due to loose or displaced guide rails. 60

Having thus described the invention what I claim and desire to cover by Letters Patent is:

1. A spacer block constructed to be arranged between a guard rail and another 65 rail, said block being provided with a portion which engages the under side of said rails and provides a support for said rails, said block having means whereby a clamping element which engages said rails and has a portion which is disposed below said rails 70 is held against movement relatively to said block.

2. A spacer block constructed to be arranged between a guard rail and another 75 rail said spacer block having a portion which extends below said rails and provides grooves for the reception of the flanges of said guard rail and second mentioned rail, said portion which extends below said rails 80 providing means for holding a clamping element which engages the web and flange of said rails against movement relatively to said block.

3. A spacer block constructed to be arranged between a guard rail and another 85 rail, said block being provided with a portion which engages the adjacent faces of said rails and having recesses for the reception of the flanges of said rails said block 90 providing portions which extend below said rails and provide a support for said rails, said portion which extends below said rails being provided with means for receiving a clamping element, a portion of which is disposed below said rails. 95

4. A spacer block constructed to be arranged between a guard rail and another rail, said block being provided with portions which are spaced apart from each other and engage the under side of said rails, and a separable clamping element which engages the rail and has a portion which is adapted to be arranged in said space, to hold the clamping element against movement relatively to 100 said block. 105

In witness whereof, I hereunto subscribe my name this 21st day of July, A. D. 1922.

CHARLES J. HOHMAN, Sr.
